(Cl. 226—88)

This invention relates to machines for applying closures to or removing them from containers and its object is to provide in or for such machines improved closure applying or removing apparatus.

It is primarily intended to make the apparatus constituting the invention in a form suitable for inserting screw stoppers into bottles or other containers but the invention is not limited in this respect as the said apparatus may be adapted for applying other forms of screw or screw-like closures to containers, for instance caps to bottles or tins, covers to jars or like containers and it may be adapted for other closures and containers where for applying the closure a relative rotation between the closure and container is required.

Although mainly intended for applying screw or screw-like closures as aforesaid, the apparatus constituting the invention may in some cases be adapted for use for the purpose of removing the closure from the container, for example removing screw stoppers from bottles.

Further, the apparatus constituting the invention may be made in a form suitable for applying closures to containers where no relative rotation between the closure and container is required, as for example the insertion of corks into bottles and the application of crown corks or caps to bottles and like containers.

In the improved apparatus the means for dealing with—that is applying or removing—closures are operated by fluid pressure, preferably compressed air but a liquid such as oil or water may be employed.

The apparatus constituting the invention comprises a double cylinder and piston arrangement one cylinder and piston serving to operate or control a chuck or other suitable holder for the closure and the other cylinder and piston serving to move the chuck or holder towards and from the container.

In the accompanying drawings,

Figure 1 is a vertical sectional view of one form of the improved closure or applying apparatus wherein the two cylinders thereof are arranged tandem fashion in axial alignment.

Figure 2 is a front view of a housing associated with the apparatus and adapted to accommodate a valve for controlling the fluid pressure.

Figure 3 is a view similar to Figure 2 but with certain parts thereof removed.

Figure 4 is a sectional view taken on the line IV—IV of Figure 2.

Figure 5 is a detail view of the valve aforesaid.

Figure 6 is a front elevational view of a machine for inserting screw stoppers into bottles and embodying a plurality of closure applying units of the form illustrated in Figure 1.

Figure 7 is a vertical sectional view of the same.

Figure 8 is an enlarged plan view, partly in section, of part of the said machine.

Figure 9 is a diagrammatic layout of certain parts of the machine illustrating more particularly the various stages in the operation of the means for controlling the fluid pressure to the closure applying units.

Figure 10 is an elevational view of an arrangement whereby the admission of fluid pressure to a closure applying unit is obtained only in the event of a bottle being presented to said unit.

Figure 11 is a similar view of an arrangement whereby in the event of a screw stopper not being delivered for application to a bottle the fluid pressure to the corresponding closure applying unit is relieved shortly after being admitted.

Figure 12 is a side view of a part of said means.

Figure 13 is a detail view of one of the tappets which are employed to control the fluid pressure to various closure applying units.

Figure 14 is a view similar to Figure 1 illustrating another form of the improved apparatus wherein the two cylinders thereof are arranged one within the other.

Figure 15 is a view of the upper portion of the apparatus shown in Figure 14 illustrating a modification.

Figure 16 is a detail view hereinafter to be described.

Figures 6, 7 and 9 are drawn to a smaller scale and Figures 8, 10, 11, 12 and 13 to a larger scale than the remainder of the figures.

Like parts are designated by similar reference characters throughout the drawings.

The form of the apparatus illustrated in Figure 1 will first be described, and for purpose of convenience in this description it will be assumed that the bottle to be stoppered is to stand vertically and that the closure applying or removing apparatus is arranged in an upright position over the bottle position. The main cylinder is designated by the reference numeral 1 and is intended to be fastened in the appropriate position for use in relation both to a support and to means for holding a bottle in proper position for reception of a stopper. For this purpose the lower end of the cylinder 1 is conveniently screw-threaded as at 1a so that it can be screwed into an outstanding lug 2a formed or provided on a

supporting bracket 2. This bracket may be formed on a suitable part of a machine (as hereinafter explained) or it may be adapted to be secured in situ.

- 5 At its upper end the cylinder 1 is covered by a cap or cover 3 of mainly cylindrical form the lower edge of the skirt of which fits within the cylinder. The cap is formed with an annular flange 3a which rests upon a supporting ring 4
 10 screwed on to the outside of the cylinder at the extreme upper end thereof and is surmounted by a part 3b adapted to support the means hereinafter to be described for controlling the fluid pressure to the apparatus. At its lower end the
 15 cylinder 1 has a gland or stuffing box 5 through which is adapted to slide a plunger-like body 6. The body 6 is of tubular form and the external diameter thereof is less than the inner diameter of the cylinder 1 so that between the two there
 20 is an annular space a. Near its upper end the said plunger-like body has on the outside of it an annular flange 6a which is adapted to support a series of rings and suitable packing washers held up to it by a nut or nuts on the end of
 25 the body. The various rings and washers constitute a piston having a sliding fluid-tight fit in the bore of the cylinder 1. In the specific example illustrated the said piston includes a lower ring 7 which rests on the flange 6a, a central ring 8 and an upper ring 7a, the three rings being so shaped as to be enabled to accommodate
 30 between them two packing washers such as 9. These rings and washers are held up to the flange 6a by a nut 10 which is screwed on to the outside
 35 of the plunger-like body 6. At the extreme upper end of the said body is a further ring 11 which constitutes the upper part of the piston and is screwed on to the body next to the nut 10. The ring 11 is of special formation for a purpose
 40 hereinafter to be described.
 40 Screwed into the lower end of the body 6 is a bush 12 which is internally screw-threaded as at 12a and has passing through it an Archimedean screw 13 fitted on its upper end with a nut 14 to limit downward screwing motion of the screw
 45 through the bush. The Archimedean screw 13 has attached to or, as shown, formed upon its lower end the second cylinder 15 of the apparatus. This cylinder is smaller than the main
 50 cylinder 1 and, as will be seen, is arranged in axial alignment therewith. A hollow chuck body 16 which houses the upper ends of a pair of chuck jaws 17 is screwed into or, as shown, onto the lower end of the cylinder 15. These jaws are kept in place in the chuck body 16 by a flanged
 55 collar 18 screwed upon the outside of the said body and fastened by a locknut 19. The lower ends of the jaws project downwards through and below the collar 18 and are interiorly shaped in
 60 a suitable manner to receive and hold the circular head of a screw stopper.
 65 The jaws 17 are capable of a pivotal movement in the chuck body 16 so that the said lower ends can be moved relatively towards and from each other to close and open the chuck for respectively gripping and releasing the stoppers. To this end each jaw has a rounded flange-like projection 17a on the outside disposed about midway between the opposite ends and these projections
 70 are located in an annular space b between opposing faces on the collar 18 and chuck body. The jaws are vertically arranged in the chuck and free to tilt or rock on the aforesaid projections which serve as pivots, the arrangement being
 75 such that when the upper ends of the jaws move

inwards i. e. towards each other the lower ends move outwards i. e. away from each other, and vice versa.

Passing centrally and longitudinally through a transverse partition 16a in the chuck body 16 is a rod 20 the upper end of which extends into the cylinder 15 and has fastened upon it a piston of suitable form capable of sliding and having a fluid-tight fit within the said cylinder. In the specific construction illustrated this piston is constituted by two rings 21 and 22 mounted on the upper end of the slide rod (or piston rod) 20 which is suitably reduced to form a circumferential shoulder 20a adapted to support the rings. A packing washer 23 is interposed between the two rings and the latter are held up to the shoulder 20a by means of a nut 24. The part of the rod 20 which extends from the partition 16a is of such length as to space the piston away from the partition. Surrounding this part of the rod 20 is a helical compression spring 25 the opposite ends of which bear against the underside of the associated piston and the partition 16a respectively. The natural and normal action of this spring is to move the said piston upwards away from the partition thereby lifting the rod 20.

The lower end of the slide rod 20 extends down between the jaws 17 and at or near its extremity is enlarged or has rounded humps 20b on its opposite sides and is thereby adapted to act against inclined faces 17b on the inside of the jaws disposed below the pivots. Above the pivots and near their upper ends the jaws are recessed on the inside as at 17c and on its opposite sides adjacent to the recesses in the jaws the slide rod 20 is similarly recessed as at 20c. Located between the recessed slide rod and jaws are toggle blocks or levers 26 which have their inner ends disposed in the recesses 17c while their outer ends are disposed in the recesses 20c. The arrangement of the parts described is such that a downward movement of the rod 20 in relation to the screw 13 and chuck body 16 tends to straighten the toggle blocks or levers 26 so that the latter push the upper ends of the chuck jaws 17 outwards thus closing the lower ends towards each other, and an upward movement of the said rod in relation to the screw and chuck body breaks the toggle upwards and the enlarged or humped parts 20b act against the opposing inclines 17b to force the lower ends of the jaws away from each other. In this way relative movement between the slide rod and screw 13 in one direction closes the chuck and relative movement between the said parts in the other direction opens the chuck. Thus the normal action of the spring 25 is to open the chuck.

Assuming the nut 14 to be resting on the upper end of the threaded bush 12 and the plunger-like body 6 to be held from movement within the cylinder 1, then fluid pressure in the lower cylinder 15 is high enough to overcome the resistance of the spring 25 and will press the piston associated with the rod 20 downwards and thus close the chuck jaws 17; upon said fluid pressure being released or dropped below that of the said spring the latter will re-act and lift the piston and rod to open the chuck jaws.

The bush 12 projects below the lower end of the plunger-like body 6 and fits within a bracket 27 suitably attached to or fitted on said body. A tongue piece 27a formed on the bracket 27 at the rear thereof is adapted to project into a vertical guideway 28, the arrangement being such that as the plunger-like body moves up and down

the tongue-piece slides up and down the guide-way and consequently prevents the body from turning. Conveniently, and as shown, the bush 12 is formed at its lower end with a circumferential flange 12b which fits in an enlarged lower portion of the bore 27b in the bracket 27.

In order to allow the downward movement of the rod 29 to occur within the cylinder 15 to close the chuck before downward movement of the plunger-like body 6 takes place there is provided an abutment with which the bracket 27 or a part thereon makes contact. Conveniently the abutment consists of a short horizontal portion of a cam 29 (the form of which will be hereinafter described) and a roller 30 mounted to rotate in the bracket 27 is arranged to make contact with this cam. The roller 30 is mounted to rotate about a stud 31 suitably screwed into the bracket and ball bearings 32 are provided to enable the roller to run smoothly. After closure of the chuck the cylinder apparatus moves bodily, as will be described later herein, so that the roller or equivalent part on the bracket 27 rides down an inclined part of the cam 29 whereupon the body 6 and Archimedean screw 13 move downwards until the stopper is arrested by contact with the bottle after which the body 6 continues its downward movement during which the screw-threaded bush 12 acting as a nut imparts rotation to the screw thus screwing the stopper into the bottle.

Since both the movement of the stopper to the bottle and the screwing of the stopper in the bottle is effected by the action of a fluid medium, preferably compressed air, the closure applying apparatus operates with a degree of flexibility which permits temporary retardation, if required, while the thread on the screw stopper feels for and finds the thread in the bottle throat and which also permits the rotary motion of the stopper and chuck to be arrested by the tightening of the stopper in the bottle against the pressure of the acting fluid medium. In other words the acting fluid medium, especially when aeriform, acts like a cushion so that as the screw stopper is being applied to the bottle the pressure downwards on the bottle and also rotationally on the stopper is yieldingly applied which method facilitates correct entrance of the screw shank of the stopper into the screw throat of the bottle for commencement of the screwing in motion and also enables the stopper to be screwed tightly down, it being understood that the pressure of the acting fluid is regulated to act within the strength of the bottle and closure to prevent breakage of either.

In the example now being described fluid pressure is admitted to the lower cylinder 15 to act on the piston therein and hence move the rod 29 downwards to close the jaws 17 through a tube 33 of comparatively small diameter which extends longitudinally through the centre of the plunger-like body 6 and also through the screw 13, which latter is formed with a central bore 13a to permit of the passage of the tube. At its upper end the central tube extends both through the cap 3 and a bore in the part 3b and is screwed into the bottom of a housing 34 which is mounted on and supported by the said part. This housing is adapted to accommodate means, for example, and as shown, a two-way valve such as 35, for controlling the admission and exhaust of fluid pressure to and from the apparatus and is formed at the bottom thereof with a flange 34a which is adapted to fit into a recess in the top of the part 3b and to be held down by means of one or more screws, such as 36. The central tube 33 communicates with the

interior of the valve housing through a small hole 37 which in turn connects with a vertical passage 38. Fluid is also exhausted from the cylinder 15 at the appropriate times through the tube 33 in the manner hereinafter more fully described. In the region of the upper end of the bush 12 the tube 33 passes through packing elements, such as 39 and 40, which are accommodated in a small cylindrical chamber 41 screwed onto the upper end of the Archimedean screw 13 next to the nut 14.

A suitable hole, such as 42, is provided in the cap 3 for the admission and exhaust of fluid to and from the main cylinder 1 and such fluid is conveyed from the valve housing 34 to the interior of the cap by means of a pipe 43. In Figure 1 this pipe is shown in dot-and-dash lines since it would not actually appear in the sectional view shown. An inlet 44 is provided at or near the bottom of the cylinder 1 for fluid to act upon the underside of the piston associated with the plunger-like body 6 to move the latter upwards at the appropriate times. In the preferred arrangement the cylinder 1 below the piston therein is permanently subject to fluid pressure. Thus, when the valve 35 is appropriately manipulated to admit pressure to the upper end of the cylinder 1 the plunger-like body 6 is moved down against the pressure below the piston on said body due to the difference in cross-sectional area; after such movement and by opening the valve to exhaust the pressure in the upper part of the main cylinder 1 the plunger-like body 6 is raised again.

Now, as will be readily appreciated, the residual air within the plunger-like body 6 is compressed when the latter is moved down. The pressure of this residual air acts on the top of the chamber 41 and hence also on the screw 13 and would be sufficient to cause breakage to the stoppers and/or the bottles if means were not provided to permit of the escape of the air from the interior of the body 6 during its downward movement. To enable such escape means of any suitable character may be provided. In the form of the apparatus now being described the said means comprise an open-ended tube 45 which is arranged to surround the central tube 33 and adapted to communicate with the atmosphere at its upper end. The internal diameter of the tube 45 is greater than the external diameter of the tube 33 so that between the two tubes there is an annular space c. At its upper end the tube 45 is screwed into the part 3b and retained in position by a nut 46. At this end, moreover, the said tube is open to a chamber d within the part 3b which chamber connects with an outlet 47. If desired, and as shown, a nipple such as 48 may be associated with the outlet so that the latter can also serve, when required, for the admission of lubricant. The arrangement just described is therefore such that whenever the body 6 moves downwards the residual air therein is forced up the annular space c and out through the outlet 47. In passing it may be mentioned that the chamber d also accommodates a nut 49 which retains the tube 33 in position. The tube 45 passes through and is prevented from lateral displacement by the ring 11 aforesaid which is carried up over the top of the body 6 and formed with an axial bore of approximately the same diameter as the external diameter of the tube. The upper portion of the ring 11 is recessed for the reception of a packing washer 50 and is covered at the top by a member 51. The length of the tube 45 is such that it is at all times surrounded by the ring 11. The hous-

ing 34 aforesaid and the valve 35 for controlling the fluid pressure will now be described more fully with reference to Figures 2, 3, 4 and 5. As will be seen, the housing is provided with a valve chamber 34b of cylindrical form which is open at one side, i. e. at the rear, but normally adapted to be closed by a cover 52. This cover is conveniently screwed into the chamber and formed with an outwardly projecting boss 52a in which is fitted one end of a pipe 43 for the supply of fluid to the chamber (see Figure 4). The valve 35 is conveniently of a rotary character and consists of a disc which, as shown in Figure 5, is formed on one side thereof with an inlet port 35a and two exhaust ports 35b and 35c. All three ports are in the form of slots, the depth of which is approximately half the width of the valve. The port 35a is of arcuate form and is formed centrally thereof with a hole 35d which extends through to the opposite side of the valve, while the two ports 35b and 35c are of shorter extent and obliquely disposed. The valve is adapted to be fitted on the end of a spindle 54 mounted to rotate in a suitable bearing 34c which constitutes a part of the valve housing and projects forwardly from the chamber 34b. When the valve is in position it is accommodated within the chamber with the side thereof formed with the inlet and exhaust ports flat against the inner wall of said chamber, the cover 52 being shaped so as to provide a space between it and the other side of the valve. A short passage or hole 55 is provided between the pipe 43 and the valve chamber and two holes 56 and 57 formed in the casing 34 (see more particularly Figure 3) serve to exhaust fluid pressure from the cylinders of the apparatus at the appropriate times.

The valve arrangement is such that when the spindle 54 is rotated to bring the valve into the position indicated in Figure 5, the exhaust port 35b connects the holes 37 and 56 and the port 35c similarly connects the holes 55 and 57 so that fluid in the cylinders 1 and 15 is exhausted. If now the valve is turned through approximately 90° in a clockwise direction, the said exhaust ports are moved clear of the various holes and the inlet port 35a covers the hole 55 thus admitting fluid pressure to the main cylinder 1 only. By suitably turning the valve spindle the inlet port 35a can be made to cover the hole 37 alone, or it can be made to cover both the holes 37 and 55 to admit fluid pressure to cylinders 1 and 15 simultaneously. Moreover, the arrangement of the various holes and ports is such that the valve 35 can be turned to such a position that the holes 37 and 55 are both closed and by doing this at an appropriate time an earlier cut off can be achieved for the purpose aforesaid.

The closure applying apparatus described may be adapted for use as a single unit the fluid pressure being controlled manually, by pedal or mechanically. Two or more of such units may be associated for use, in which case they may be subject to individual or common fluid pressure control.

However, the improved apparatus is mainly intended for embodiment in a machine for automatically applying screwed stoppers to bottles. A machine suitable for this purpose will now be described with reference to Figures 6-13.

As shown in Figures 6 and 7, the machine is provided with a circular drum 58 arranged to revolve about a vertical axis. This drum carries on the outside of it a plurality of the closure applying units described with reference to Fig-

ures 1-5, the brackets 2 supporting the main cylinder 1 being rigidly attached in any suitable manner to the periphery of the drum, conveniently at the upper end thereof. The axes of the closure applying units are vertical and suitably spaced apart around the drum. The drum periphery also has in it, or, as shown in Figure 7, on it a series of vertical guideways 28 for reception of the tongues 21a on the slideable brackets 21 aforesaid. The drum is secured to a spindle 59 which is vertically disposed and mounted to rotate in suitable bearings in the machine frame. In the specific example illustrated, the upper end of the spindle is mounted in a bearing 60a formed on a plate 60 whilst the lower end thereof is journalled in a bearing 61a formed on a pedestal or base portion 61. A nut 62 serves to prevent the spindle from axial displacement. The plate 60 is disposed above the closure applying units and is bolted to a ring 63 supported on vertical columns, such as 64, which are conveniently mounted at their lower ends in sockets or equivalent parts 65 formed or provided on the base portion 61. The spindle 59 is adapted to be driven by any suitable means. Conveniently it is driven from a main shaft 66 through gearing such as 67, 68 accommodated in a housing 69 provided at the upper end of the pedestal or base portion and adapted to serve as an oil bath. The gearing in the specific example illustrated comprises a worm 67 on the shaft 66 which meshes with and drives a worm wheel 68 adapted to rotate the spindle and for this purpose bolted to a flange 70a on a collar 70 rigidly secured to the spindle. The main shaft 66 extends through the housing 69 and has attached thereto a driving pulley 71 adapted to be driven, e. g. from a motor or belt shafting (see Figure 6).

A circumferential flange 70b formed at the upper end of the collar 70 constitutes an annular shelf or table to support the bottles to be stoppered. In Figures 6 and 7 such bottles are indicated at 72 and stoppered bottles at 73. The shelf or table is, of course, positioned below the jaws 17 of the various chucks and extends at right angles to the drum axis. Alternatively the shelf or table may be formed on the drum 58 which latter would then be carried down to a lower extent than shown. Centrally below each closure applying unit the shelf or table may, as shown, be recessed for the reception of a bottle supporting pad 74. The bottles 72 to be stoppered are carried to the machine by a conveyor such as 75, from which they are taken by a suitable transferring device, such as 76. The conveyor is arranged tangentially to the bottle carrier shelf or table and has associated therewith rails, such as 77, to guide the bottles 72 into the device 76 and from said device onto the shelf or table 70b. The device is conveniently of star-wheel formation (see Figure 8) and is so shaped as to be capable of placing each bottle in register with the screw 13 and chuck jaws 17 of the corresponding closure applying unit. The transferring device 76, moreover, is removably mounted on a short vertical spindle 78 and is adapted to be driven in timed relation with the operation of the machine. In the specific example being described the spindle 78 is rotatably mounted in a bracket 79 secured to one of the columns 64 below the upper run of the conveyor and has associated therewith a gear wheel 80 arranged to mesh with another gear wheel 81 bolted to the underside of the shelf or table 70b. By making the transferring device removable it can be

readily changed for a device of another size to suit different sized bottles. A device 82 similar to the device 76 is provided at the opposite side of the machine to transfer stoppered bottles 73 from the shelf or table 70b back on to the conveyor which latter then delivers the bottles from the machine. The pads 74 aforesaid are preferably made of rubber or similar material having a non-slip surface and in this way each bottle 10 is effectively prevented from rotating while it is being stoppered. Alternatively, and for the same purpose, means of any suitable character may be provided for holding the bottles firmly during their travel on the shelf or table.

15 The screw stoppers for the bottles, such as that indicated at 83, are taken e. g. mechanically, from a hopper (not shown) and by appropriate means now to be described are brought one at a time into a position in the circular path of the 20 travelling chucks. The stoppers are fed into chambers 84a provided in a circular magazine 84 which is adapted to be intermittently rotated in timed relation with the operation of the machine to bring the chambers successively into the vertical 25 stopper taking position indicated at f, Figure 6, where they register with a slot 85 in the magazine casing 86 or in a cover plate, such as 86a (Figure 8) applied thereto. In Figure 7 this cover has been removed to reveal the magazine 30 chambers 84a. Each chuck approaches the position f with its jaws 17 open and when it reaches the stopper in the chamber which is then at this position, it pushes the stopper from the magazine, through the slot 85, and along a short 35 curved track 87 concentric with the axis of the drum 58. As shown clearly in Figure 8, this track consists of two curved guide rails 87a which are arranged parallel to each other and secured at their inner ends to the magazine casing. The 40 flanged head of a stopper is supported on the upper edges of the rails while the screwed shank thereof extends downwardly between the sides of the rails (see Figure 11). During the time a stopper is moved along the track 87 the jaws 17 45 of the corresponding chuck are closed to grip the stopper.

The casing 86 is mounted on a bracket 88 secured to any suitable stationary part of the machine, whilst the magazine itself is attached to a spindle 89 which is rotatably mounted in the said casing and adapted to be intermittently rotated through a fractional part of a revolution. For this purpose the spindle has on it a worm 50 wheel 90 which meshes with a worm 91 associated with a vertical spindle 92 mounted to rotate, e. g. in suitable bearings in the magazine bracket 88. Attached to this spindle is a star-wheel 93 which is adapted to be racked round at the appropriate times by means of a circular 55 series of cams or equivalent elements rotating at the same speed as the various other rotary parts of the machine. Conveniently, and as shown in Figures 6, 7 and 8, the star-wheel 93 is racked round by a circular series of rollers 94 which act 60 on the radially extending arms of the wheel in succession. Each of these rollers is mounted on the underside of a plate 95 which is attached to, e. g. by a bolt 96, and projects radially from a flange 97a on a flanged collar 97 which 65 rounds the central spindle 59 and is interposed between the lower end of the drum 58 and the bottle shelf or table 70b. The collar 97 is bolted to the said drum and the shelf or table so that it rotates in company therewith. To prevent the 70 star-wheel from rotating between racking move- 75

ments it is formed with a part 93a having a series of flat surfaces one of which is brought into and remains for the required time in contact with an upstanding part 95a on one of the plates 95 after each partial rotation of the wheel. 5 One of the parts 95a is formed or provided on the top of each plate 95 and operates in the manner illustrated clearly in Figure 8.

The arrangement just described is therefore such that stoppers 83 previously inserted in the 10 chambers 84a are brought one at a time to the stopper-taking position f. Moreover, it should be understood that the chucks take a stopper one after another as they come around to this position and after each stopper has been taken 15 by a chuck another is brought into position for the next chuck coming around.

The movements of the plunger-like bodies 6 of the various closure applying units are controlled, that is to say, said bodies are prevented from 20 moving too quickly, by a cam 29 which, in the specific example illustrated, is of the form illustrated more clearly in Figure 9 and is arranged to surround the circular series of units. The rollers 30 run on the cam as hereinafter more 25 fully explained and the latter is supported on small brackets, such as 98, Figure 7, which are attached for example by bolts 99 to the columns 64 aforesaid.

From a central box or chamber 100 on the top 30 of the revolving drum 58, suitable pipe connections are made to the valve housings 34 and cylinders 1 of the closure applying units and compressed air is supplied to the box or chamber through a pipe 101 which conveniently communicates with suitable passages 59a, 59b in the central spindle 59. In the arrangement illustrated a pipe 102 connects each of the inlets 44 aforesaid with the air box or chamber while each of the pipes 53 for supplying air to the valve housings 34 are connected with the pipe 102 of the corresponding unit, e. g. by a T such as 103.

In this machine the valve spindle 54 of each closure applying unit projects outwardly from the corresponding bearing 34c and is fitted with 45 arms for rotating it. Each spindle is furnished with a two-limbed front arm 104, a single-armed rear arm 105 extending at right angles to the arm 104 and a middle arm 106 which is similar to, but extends in the opposite direction to the 50 said rear arm. The three arms are suitably spaced apart by collars 107 and are retained in position by a nut 108 screwed on to the outer end of the valve spindle (see more particularly Figure 4).

As will be seen, the arms associated with the various valve spindles 54 are disposed near to the stationary ring 63 aforesaid and the said arms are operated at the appropriate times by tappets associated with and suitably spaced apart 60 around the ring. As the arms revolve with the units on the drum 58 they make contact with the said tappets and by such contact are turned to operate the two-way valves 35 in a manner necessary to effect correct operation of the closure applying units.

One of these tappets is indicated at 109 and is mounted beneath the ring 63 at a position A (Figure 9) just in advance of the stopper-taking position f. This tappet is adapted to act on the 70 rear arms 105 to open the valves 35 to admit compressed air to the main cylinders 1 and is associated with mechanism whereby such admission of air is obtained only in the event of a bottle 72 being presented to the machine. The said mech- 75

anism conveniently consists, as shown in Figures 6, 8 and 10, of a lever 110 located in the path of the bottles 72 and connected with the tappet 109 which is movably arranged. In the specific arrangement illustrated, the tappet 109, which may be quadrant-shaped, is mounted on a rock-shaft 111 carried horizontally and mounted to rotate in brackets 112 and 113 bolted to the underside of the ring 63. The intermediate connections between the shaft 111 and the lever 110 consist of bevel gearing such as 114, 115, and a vertical rockshaft 116 to which the lever is attached. Normally the tappet is located out of the path of the arms 105 aforesaid but is moved into the said path when a bottle 72 makes contact with and as a result moves the lever 110. Spring means such as 117 may, as shown, be provided for restoring the mechanism to normal position after operation by a bottle. If the lever 110 is not operated by a bottle so that pressure is not admitted to the cylinder 1 of the corresponding closure applying unit, the operations which normally take place in said unit subsequent to such pressure admission are not performed. Now, the closure applying units approach the tappet 109 in succession with the rollers 30 in contact with the raised portion 29a of the cam 29 (see Figure 9). Thus if pressure is admitted to the main cylinder 1 of a unit in the manner just described the corresponding plunger-like body 6 is first moved down slightly to an extent permitted by the cam 29 (that is to say until the roller 30 rests on the horizontal part 29b of said cam) and as a consequence the chuck descends open upon a stopper in the magazine 84. On the other hand, if pressure is not admitted to the main cylinder of a unit the latter moves round the machine with its roller 30 on the level X and the chuck jaws 17 on a level Y clear of the stopper magazine.

An arrangement of the character described whereby admission of fluid pressure is obtained only in the event of a container being presented to the machine may, of course, also be applied to a machine provided with only one closure applying unit.

Another tappet, such as 118, is provided at position B, this tappet being adapted to act on one limb of each of the front arms 104 to effect operation of the two-way valves 35 in such a manner as to close the jaws 17 of the chucks by admitting compressed air to the lower cylinders 15. The tappet 118 is associated with mechanism whereby in the event of a screw stopper 63 not being delivered for application to a bottle the pressure in the main cylinder 1 of the corresponding closure applying unit is relieved shortly after being admitted, and this mechanism will now be described with reference to Figures 6, 8, 11 and 12. Conveniently the mechanism comprises a lever 119 adapted to be acted upon by a screw stopper and intermediate parts adapted to effect operation of a valve 35 to open the exhaust passages in the event of the lever not being acted upon by a stopper.

The lever 119 is pivotally mounted between the two rails 87a of the curved track 87 aforesaid and is attached to one end of a short spindle 120 which is rotatably mounted in a bearing 121 formed or provided on the magazine casing 86 or a part associated therewith. Rigidly secured to the opposite end of the spindle 120 is an arm 122 to the outer end of which is attached a coupling member 123 which serves to connect the arm with a vertical rod 124, and the arrangement is such

that as a stopper is moved by a chuck along the track 87, the lower end of the shank of the stopper makes contact with and depresses the lever 119 with the result that the arm 122 is turned and the rod 124 pulled downwardly. Conveniently, and as shown more clearly in Figure 11, a pin-and-slot connection is provided between the arm and the member 123. The tappet 118 in the specific arrangement shown consists of a small bar which is slidable in a bracket 125 bolted to the underside of the ring 63. An auxiliary tappet 126 of similar form is mounted to slide in the said bracket and is disposed below and parallel to the tappet 118 so that it can act on the other limbs of the front arms 104. The two tappets are linked together by a pivoted member 127 which is secured to a spindle 128 rotatably mounted in the bracket 125. This spindle extends between the tappets 118 and 126 at right angles thereto and at one end projects laterally from the bracket 20 where it is connected to the upper end of the rod 124, for example, by means of an intermediate connecting link, such as 129. A spring 130 (see Figure 6) normally acts to retain the parts of the mechanism just described in the positions indicated in Figures 11 and 12, with the operative end of the tappet 126 projecting from the bracket 125 and the corresponding end of the tappet 118 withdrawn. That is to say, the tappet 126 normally occupies an operative position in relation to the path of the front arms 104 while the tappet 118 normally occupies an inoperative position in relation to said path.

Now, if a stopper is properly delivered it depresses the lever 119 with the result that the tappet 118 is projected and the tappet 126 withdrawn. Consequently as the next closure applying unit passes the position B, the appropriate limb of the arm 104 thereof is operated by the tappet 118 and pressure is admitted to the cylinder 15 of the unit. If, however, a stopper is not delivered, the tappet 126 acts on the other limb of the said arm and rotates the valve to such a position that pressure is exhausted from the main cylinder 1 of the unit—which otherwise would have received the stopper.

A stationary tappet 131 suitably spaced apart from the admission tappets 109 and 118 in the circular path of the tappet-operated arms is provided to act on the front arms 104 so that the valve associated with each front arm so acted upon is turned again to the position indicated in Figure 5 to open to exhaust both cylinders of the corresponding closure applying unit. This tappet which, as shown in detail in Figure 13, conveniently consists of a roller mounted on a bracket 132 bolted to the underside of the ring 63 is so positioned (approximately at D, Figure 9) that the front arm of a closure applying unit is acted upon for the intended purpose immediately said unit has inserted a stopper into a bottle.

In the machine illustrated the air supply to each unit is maintained for the major portion of the stopper inserting operation, after which the supply to said unit is cut off to enable the air therein to work expansively as hereinbefore mentioned. For this latter purpose a tappet 133 of a form similar to the exhaust tappet 131 and mounted on a bracket 134 is provided at C, i. e. in advance of the said exhaust tappet, and is adapted to act on the middle arms 106—as the units come around—so that the valves are turned to positions wherein neither the pressure nor the exhaust passages therein are opened and by doing this an earlier cut off can be achieved.

When finally both the cylinders of any of the closure applying units are exhausted, the chuck jaws 17 open and the various parts are returned to normal position as previously described.

5 In explanation of Figure 9 it should here be mentioned that the distance *g* represents the complete circumference of the machine. Moreover, the closure applying units travel in the direction of the arrow marked on this figure and 10 while it appears at first sight that the tappets 131 and 133 are positioned in advance of the admission tappets 109 and 118, this is not so since each stopper applying operation commences at the point A. As will be seen, the horizontal 15 portion 29b of the cam 29 is of such length as to support those rollers 30 previously moved down into contact with said portion and prevent the corresponding plunger-like bodies 6 from moving downwardly to take the stoppers to the bottles 20 until the jaws 17 of the corresponding chucks have been closed to grip the stoppers. After this has been done each of the said rollers in turn rides down an inclined part 29c of the cam to control the downward movement of the corresponding plunger-like body 6 and subsequently 25 rides up an oppositely inclined part 29d to control the upward movement of said body after the termination of a stoppering operation.

In this machine the bottles, during the stoppering operations, are carried around the axis of the machine by the revolving drum 58 but they do not rotate about their own axes, the necessary rotation for screwing in the stoppers being effected by the Archimedean screws 13 and the 35 associated chucks.

Instead of having a plurality of closure applying units the machine herein described may be provided with only one such unit.

The constructional form of the apparatus 40 illustrated in Figures 14 and 16 will now be described.

The outer cylinder 135 is closed by a cover, such as 136, or otherwise at its upper end while at its lower end it has a gland or stuffing box 137 through which the body of the inner cylinder 138 slides as a piston rod or plunger. The inner cylinder is of tubular form the external diameter of its body being less than the inner diameter of the outer cylinder so that between the two 45 there is an annular space. Near its upper end the inner cylinder body 138 has on the outside of it an annular flange 138a which in conjunction with suitable packing washers, such as 139, and rings 140 and 141 held up to it by nuts, such as 50 142, on the end of the cylinder body forms a piston having a sliding fluid-tight fit in the bore of the outer cylinder 135.

The upper end of the inner cylinder is open to the interior of the outer cylinder. Screwed into 55 the lower end of the inner cylinder 138 is a bush 143 held by a locknut 144 so that the bush can be adjusted in the cylinder. This bush is internally screw threaded as at 143a and has passing through it an Archimedean screw 145 fitted on its upper end with a nut 146 and locknut 147 to limit downward screwing motion of the screw 60 through the threaded bush. The Archimedean screw has formed upon or attached to its lower end a hollow chuck body 148 which houses the upper ends of a pair of chuck jaws 17. These jaws are kept in place in the chuck body by a flanged collar 149 screwed upon the outside of the said body and fastened by a locknut 150. The lower ends of the jaws project downwards 65 through and below the collar and are interiorly

shaped in a suitable manner to receive and hold the circular head, such as 151, of a screw stopper.

The jaws will not be particularly described since the construction thereof is precisely the same as that of the jaws in the previously described form of the apparatus. 5

Passing centrally and longitudinally through the screw 145 is a rod 20' capable of endwise movement in the screw. The lower end of this rod extends down between the jaws 17 and engages the latter in the same manner in which the rod 20 engages the jaws in the first described apparatus.

The upper end of the slide rod 20' extends through and beyond the upper end of the 15 Archimedean screw and it has fastened upon it a piston 153 of suitable form capable of sliding and having a fluid-tight fit within the inner cylinder 138. The part of the slide rod which extends from the upper end of the screw is of 20 such length as to space the piston away from the locknut 147. Surrounding this exposed part of the rod is a helical compression spring 154 the opposite ends of which bear against the underside of the piston 153 and the locknut 147 25 respectively. The natural and normal action of this spring is to move the piston upwards away from the screw 145 thereby lifting the slide rod 20' and opening the chuck jaws.

The screw-threaded bush 143 projects below 30 the lower end of the inner cylinder and is enlarged in diameter to form an inverted circular head 143b the periphery of which is formed with fine teeth 143c. Clamped about the toothed periphery of the head is a two-part clip 155 (one 35 part only of which is shown) having a lug 156 which projects into a vertical guideway 157. As the inner cylinder body moves up and down the lug 156 slides up and down the guideway and the clip 155 prevents the said body from turning. 40 By detaching the clip and slackening the locknut 144 the screwed bush can be turned to adjust it in the cylinder 138.

In order to allow the downward movement of the rod 20' to occur within the Archimedean screw 45 145 to close the chuck jaws 17 before downward movement of the inner cylinder body 138 takes place there is provided an abutment 158 with which the clip 155 makes contact. After closure of the chuck the abutment is displaced or the 50 apparatus moves bodily so that the clip passes off the abutment, whereupon the cylinder body and screw move downwards until the stopper is arrested by contact with the bottle in a manner similar to that mentioned in connection with the 55 previously described form of the invention.

Fluid pressure admitted to the top of the outer cylinder 135 acts upon the piston 153 in the inner cylinder 138 and this pressure also acts upon the piston on the outside of the inner cylinder 60 body to move the latter down when permitted. A suitable inlet 159 is provided at or near the bottom of the outer cylinder for fluid to act upon the underside of the piston on the inner cylinder body to move the latter upwards. 65

The fluid pressure may be controlled by any suitable means to give the action required.

It is essential that when the inner cylinder body reaches its normal raised position the Archimedean screw should assume its normal dropped 70 position. In order to prevent the bush 143 in the inner cylinder from lifting the screw 145 too high two brackets such as 160 (see Figure 16) are fixed in a suitable position each carrying a roller or small wheel 161. If when the inner 75

cylinder rises the Archimedean screw does not under the influence of gravity unscrew downwards through the bush the flange on the collar 149 comes up against the rollers or small wheels 5 which prevent the chuck from rising further. The rollers or small wheels thus act as abutments to arrest upward movement of the chuck when it reaches its normal position and during any further rise of the inner cylinder body the 10 screw, being forcibly held from further rise by the abutments, is rotated by the bush during which rotation the flange on the collar 149 runs around in contact with the rollers or wheels which themselves rotate to permit free rotation 15 of the chuck.

The rotatory abutments 161 just described by limiting the rise of the chuck may also serve to limit the rise of the inner cylinder body 138 in this way that further rise of the said body is 20 prevented when the upper end of the screw-threaded bush 143 makes contact with the nut 146. By thus ensuring that the chuck and inner cylinder body return to their proper normal positions the chuck not only occupies the proper 25 level but is also caused to assume the proper position rotationally for receiving or taking the next stopper in cases where the stoppers are automatically fed or delivered to the chuck or are taken by the chuck from a stopper feeding or 30 supplying means.

Instead of having the inner cylinder 138 open at the top to the interior of the outer cylinder 135, the inner cylinder body may have a cover 162 on its top end in which case a pipe 163 extending 35 upwards from the cover is slidable through a stuffing box or gland 164 on the top cover 139 of the outer cylinder. This pipe communicates with the interior of the inner cylinder and enables fluid pressure to be admitted to the inner and outer cylinders independently. This arrangement is similar to the arrangement described with reference to Figure 1 since it permits the chuck to be operated for opening and closing independently of the actuation of the inner cylinder body within the outer cylinder.

In this instance, moreover, the abutment 158 can be obviated as the movement of the inner cylinder body can be controlled by the fluid pressure in the outer cylinder independently of that 50 in the inner cylinder.

For removing screw stoppers with either of the forms of apparatus herein described the apparatus is arranged and operated so that the chuck descends open upon the stopper after which the 55 chuck jaws are closed to grip the stopper. The inner cylinder body is then moved upwards causing the threaded bush to impart rotation to the Archimedean screw thus unscrewing the stopper following which the removed stopper is carried 60 up by the chuck as the screw rises with the inner cylinder body.

When the improved apparatus is to be used for applying non-screw closures for example corks, crown corks, caps and the like, it may 65 have a plain rod or some equivalent member instead of a screw.

The jaws of the chuck in either of the forms of the invention herein described may be removable and interchangeable with others to enable 70 the chuck to deal with closures of different size and/or kind. For instance, by removing the flanged collar from the chuck body the jaws can be slipped out downwards and replaced by others.

The expression "apparatus for dealing with 75 containers and closures therefor" hereinafter

used in the appended claims is a generic expression intended to include both the application of closures to and removal thereof from containers.

What I claim then is:—

1. Apparatus for dealing with containers and closures therefor comprising, in combination, a holder having gripping members capable of receiving and holding between them a closure, a cylinder, a piston in said cylinder, a member associated both with said piston and the holder and adapted to close the said gripping members to grip a closure when the piston is caused to move in an appropriate direction in the cylinder, spring means associated with said member and adapted, when permitted, to effect an opening movement of the gripping members, a second cylinder, a piston in said second cylinder, said last mentioned piston being adapted when it works within said second cylinder to effect movement of the holder towards and from a container to be dealt with, and means for effecting admission and release of fluid pressure to and from the cylinders, whereby the pistons can be appropriately moved within the cylinders for the 25 intended purpose.

2. Apparatus for dealing with containers and screw closures therefor, comprising, in combination, a holder adapted to receive and grip a closure, a cylinder, a piston in said cylinder, a member associated both with said piston and the holder and adapted to operate the latter when the piston works within the cylinder, another cylinder, a piston in said second cylinder, said piston being adapted when it works within its cylinder 35 to effect movement of the holder towards and from a container to be dealt with, means in association with said second-mentioned cylinder and piston for imparting the necessary rotatory movement to the holder, and means for effecting admission and release of fluid pressure to and from the cylinders whereby the pistons can be appropriately moved within the cylinders to deal 40 with a closure and subsequently return the parts of the apparatus to normal position.

3. Apparatus for dealing with containers and closures therefor comprising, in combination, a holder adapted to receive and grip a closure, a cylinder, a piston in said cylinder, a member associated both with said piston and the holder and adapted to operate the latter when the piston works within the cylinder, another cylinder arranged tandem fashion in axial alignment with the first cylinder, a piston in said second cylinder, said piston being adapted when it works within its cylinder to effect movement of the holder towards and from a container to be dealt with, and means for effecting admission and release of fluid pressure to and from the cylinders whereby the pistons can be appropriately moved within 60 the cylinders for the intended purpose.

4. Apparatus for applying screw closures to containers comprising, in combination, a main cylinder, a plunger having upon it a piston adapted to work within said cylinder, a nut which is 65 carried by said plunger, an Archimedean screw which extends through the nut, a second cylinder on said screw, a holder associated with said second cylinder and adapted to receive and grip a closure, a piston in said second cylinder, a member associated both with the piston in the second cylinder and the holder and adapted to operate the latter when the piston works within the second cylinder, and means for effecting admission and release of fluid pressure to and from 75

the cylinders whereby the pistons can be appropriately moved within the cylinders to operate the holder so that it grips a closure, move said holder to a container to be closed, effect rotation of the holder to apply the closure and subsequently return the parts of the apparatus to normal position.

5. Apparatus for applying screw closures to containers comprising, in combination, a main cylinder, a plunger having upon it a piston adapted to work within said cylinder, a nut which is carried by said plunger, means for preventing the plunger from turning during movement thereof within the main cylinder, an Archimedean screw which extends through the nut, a second cylinder on said screw, a holder associated with said second cylinder and adapted to receive and grip a closure, a piston in said second cylinder, a member associated both with the piston in the second cylinder and the holder and adapted to operate the latter when the piston works within the second cylinder, and means for effecting admission and release of fluid pressure to and from the cylinders whereby the pistons can be appropriately moved within the cylinders to operate the holder so that it grips a closure, move said holder to a container to be closed, effect rotation of the holder to apply the closure and subsequently return the parts of the apparatus to normal position.

6. Apparatus for applying closures to containers comprising, in combination, a holder adapted to receive and grip a closure, a cylinder, a piston in said cylinder, a member associated both with said piston and the holder and adapted to operate the latter when the piston works within the cylinder, another cylinder, a piston in said second cylinder, said piston being adapted when it works within its cylinder to effect movement of the holder towards and from a container to be closed, means for effecting admission and release of fluid pressure to and from the cylinders whereby the piston in the first-mentioned cylinder can be moved to cause the holder to grip a closure, the second-mentioned piston can subsequently be moved to effect movement of said holder and the closure towards a container to be closed and, after the closure applying operation, both pistons can be moved to return the parts of the apparatus to normal position, and means for preventing operative movement of said second-mentioned piston until the holder has been operated to grip the closure.

7. Apparatus for applying screw closures to containers, comprising in combination, a main cylinder, a plunger having upon it a piston adapted to work within said cylinder, a part associated with the outer end of said plunger and having a projection thereon, a vertical guideway into which the said projection can project to prevent the plunger from turning during movement thereof within the main cylinder, a nut which is carried at the outer end of said plunger, an Archimedean screw which extends through the nut, a second cylinder on said screw, a holder associated with said second cylinder and adapted to receive and grip a closure, a piston in said second cylinder, a member associated both with the piston in the second cylinder and the holder and adapted to operate the latter when the piston works within the second cylinder, means for effecting admission and release of fluid pressure to and from the cylinders whereby the pistons can be appropriately moved within the cylinders to operate the holder so that it grips a closure,

move said holder to a container to be closed, effect rotation of the holder to apply the closure and subsequently return the parts of the apparatus to normal position, and an abutment with which the aforesaid part at the outer end of the plunger can make contact to prevent operative movement of the plunger until the holder has been operated to grip the closure.

8. A machine for dealing with containers and closures therefor comprising, in combination, apparatus including a holder adapted to receive and grip a closure, means operable by fluid pressure for operating the holder to grip said closure, and means also operable by fluid pressure for moving said holder towards and from a container to be dealt with, a support on which a container can be placed in proper position relatively to the holder, means for moving the support so that the container can be conveyed through the machine, means for causing the aforesaid apparatus to travel in company with the container, means for bringing closures into position to be received by the travelling holder, and means for automatically effecting the control of fluid pressure to and from the fluid operated means at the required times so that the holder can take a closure and deal with it at the appropriate places.

9. A machine for dealing with containers and closures therefor, comprising, in combination, a drum arranged to revolve about a vertical axis, a plurality of apparatus units each including a holder adapted to receive and grip a closure, said units with their holders disposed downwards being carried on the outside of the drum, means operable by fluid pressure for operating the holder to grip said closure, and means also operable by fluid pressure for moving said holder towards and from a container to be dealt with, a container supporting shelf adapted to rotate with the drum and disposed below the holders, means for rotating the drum so that containers placed on the shelf in proper position relatively to the holders can be conveyed through the machine, means for causing the units to travel in company with the containers, means for bringing closures into position to be received by the travelling holders, and means for automatically effecting the control of fluid pressure to and from the fluid operated means at the required times so that the holders can take closures and deal with them at the appropriate places.

10. A machine for dealing with containers and closures therefor comprising, in combination, apparatus including a holder adapted to receive and grip a closure, means operable by fluid pressure for operating the holder to grip said closure, means also operable by fluid pressure for moving said holder towards and from a container to be dealt with, a two-way valve associated with said fluid-operated means and having passages for pressure and exhaust, and arms associated with said valve and capable of being acted on for operating the valve and effecting the admission and exhaust of fluid pressure to and from the fluid operated means so that the holder can take a closure and deal with it, stationary tappets suitably spaced apart in the machine and adapted to act upon the said arms at the required times, a support on which a container can be placed in proper position relatively to the holder, means for moving the support so that the container can be conveyed through the machine, means for causing the aforesaid apparatus to travel in company with a container, and means for bringing

closures into position to be received by the travelling holder.

11. A machine for dealing with containers and closures therefor comprising, in combination, apparatus including a holder adapted to receive and grip a closure, means operable by fluid pressure for operating the holder to grip said closure, and means also operable by fluid pressure for moving said holder towards and from a container to be dealt with, a support on which a container can be placed in proper position relatively to the holder, means for moving the support so that the container can be conveyed through the machine, means for causing the aforesaid apparatus to travel in company with the container, means for bringing closures into position to be received by the travelling holder, means for automatically effecting admission and release of fluid pressure to and from the fluid operated means at the required times so that the holder can take a closure and deal with it at the appropriate places, and means for controlling said fluid pressure so that it can be cut off for a prearranged period before release, for the purpose herein described.
12. A machine for dealing with containers and closures therefor comprising, in combination, apparatus including a holder adapted to receive and grip a closure, means operable by fluid pressure for operating the holder to grip said closure, and means also operable by fluid pressure for moving said holder towards and from a container to be dealt with, a support on which a container can be placed in proper position relatively to the holder, means for moving the support so that the container can be conveyed through the machine, means for causing the aforesaid apparatus to travel in company with the container, means for bringing closures into position to be received by the travelling holder, means for automatically effecting the control of fluid pressure to and from the fluid operated means at the required times so that the holder can take a closure and deal with it at the appropriate places, and means adapted to be acted upon by a container when it is initially presented to the machine for actuating the fluid pressure controlling means to admit pressure at the required time, whereby such admission is obtained only in the event of a container being presented to the means for dealing with the closure.

13. A machine for applying closures to containers comprising, in combination, apparatus including a holder adapted to receive and grip a closure, means operable by fluid pressure for operating the holder to grip said closure, and means also operable by fluid pressure for moving said holder towards and from a container to be closed, a support on which a container can be placed in proper position for reception of a closure, means for moving the support so that the container can be conveyed through the machine, means for causing the aforesaid apparatus to travel in company with the container, means for bringing closures into position to be received by the travelling holder, means for automatically effecting the control of fluid pressure to and from the fluid operated means at the required times so that the holder can take a closure and apply it to the container at the appropriate places, and means which are normally in a position to operate the fluid controlling means to relieve the pressure near the point where a closure is initially presented to the container, said means being adapted to be rendered inoperative by a properly

delivered closure, for the purpose herein described.

14. A machine for applying screw closures to containers comprising, in combination, a drum arranged to revolve about a vertical axis, a plurality of closure applying units carried on the outside of the drum, each of said units including a main cylinder, a plunger having upon it a piston adapted to work within said cylinder, a nut which is carried by said plunger, an Archimedean screw which extends through the nut, a second cylinder on said screw, a holder associated with said second cylinder and adapted to receive and grip a closure, a piston in said second cylinder, a member associated both with the piston in the second cylinder and the holder and adapted to operate the latter when the piston works within the second cylinder, a two-way valve having passages for pressure and exhaust, and arms associated with said valve and capable of being acted upon for operating the valve and effecting admission and release of fluid pressure to and from the cylinders, whereby the pistons can be appropriately moved within the cylinders to operate the holder so that it grips a closure, move said holder to a container to be closed, effect rotation of the holder to apply the closure and subsequently return the parts of the unit to normal position, said units being disposed on the drum with their holders downwards, stationary tappets suitably spaced apart on the machine and adapted to act upon said arms at the required times, a container supporting shelf adapted to revolve with the drum and on which containers can be placed in alignment with the holders, means for rotating the drum and said supporting shelf so that the units can travel in company with the containers, and means for bringing closures one at a time into a position to be received by the travelling holders.

15. A machine as claimed in claim 14, wherein means are also provided for controlling the fluid pressure so that it can be cut off from the units for a prearranged period before release, for the purpose herein described.

16. A machine for applying screw closures to containers comprising, in combination, a drum arranged to revolve about a vertical axis, a plurality of closure applying units carried on the outside of the drum, each of said units including a main cylinder, a plunger having upon it a piston adapted to work within said cylinder, a nut which is carried by said plunger, an Archimedean screw which extends through the nut, a second cylinder on said screw, a holder associated with said second cylinder and adapted to receive and grip a closure, a piston in said second cylinder, a member associated both with the piston in the second cylinder and the holder and adapted to operate the latter when the piston works within the second cylinder, a two-way valve having passages for pressure and exhaust, and arms associated with said valve and capable of being acted upon for operating the valve and effecting admission and release of fluid pressure to and from the cylinders, whereby the pistons can be appropriately moved within the cylinders to operate the holder so that it grips a closure, move said holder to a container to be closed, effect rotation of the holder to apply the closure and subsequently return the parts of the unit to normal position, said units being disposed on the drum with their holders downwards, stationary tappets suitably spaced apart on the machine and adapted to act upon said arms at the required times.

times, a container supporting shelf adapted to revolve with the drum and on which containers can be placed in alignment with the holders, means for rotating the drum and said supporting shelf so that the units can travel in company with the containers, means for bringing closures one at a time into a position to be received by the travelling holders, and means adapted to be acted upon by a container when it is initially presented to the machine for actuating the fluid pressure controlling means to admit pressure to the corresponding closure applying unit at the required time whereby such admission is obtained only in the event of a container being presented to the means for applying the closure.

17. A machine for applying screw closures to containers comprising, in combination, a drum arranged to revolve about a vertical axis, a plurality of closure applying units carried on the outside of the drum, each of said units including a main cylinder, a plunger having upon it a piston adapted to work within said cylinder, a nut which is carried by said plunger, an Archimedean screw which extends through the nut, a second cylinder on said screw, a holder associated with said second cylinder and adapted to receive and grip a closure, a piston in said second cylinder, a member associated both with the piston in the second cylinder and the holder and adapted to operate the latter when the piston works within the second cylinder, a two-way valve having passages for pressure and exhaust, and arms associated with said valve and capable of being acted upon for operating the valve and effecting admission and release of fluid pressure to and from the cylinders, whereby the pistons can be appropriately moved within the cylinders to operate the holder so that it grips a closure, move said holder to a container to be closed, effect rotation of the holder to apply the closure and subsequently return the parts of the unit to normal position, said units being disposed on the drum with their holders downwards, stationary tappets suitably spaced apart on the machine and adapted to act upon said arms at the required times, a container supporting shelf adapted to revolve with the drum and on which containers can be placed in alignment with the holders, means for rotating the drum and said supporting shelf so that the units can travel in company with the containers, means for bringing closures one at a time into a position to be received by the travelling holders, means for controlling the fluid pressure so that it can be cut off from the units for a prearranged period before release, means adapted to be acted upon by a container when it is initially presented to the machine for actuating the fluid pressure controlling means to admit pressure to the corresponding closure applying unit at the required time whereby such admission is obtained only in the event of a container being presented to the means for applying closure, and means which are normally in a position to operate the fluid controlling means to relieve the pressure in a closure applying unit near the point where a closure is initially presented to a container, said means being adapted to be rendered inoperative by a properly delivered closure, for the purpose herein described.

18. A machine for applying screw closures to containers comprising, in combination, a drum arranged to revolve about a vertical axis, a plu-

rality of closure applying units carried on the outside of the drum, each of said units including a main cylinder, a plunger having upon it a piston adapted to work within said cylinder, a nut which is carried by said plunger, an Archimedean screw which extends through the nut, a second cylinder on said screw, a holder associated with said second cylinder and adapted to receive and grip a closure, a piston in said second cylinder, a member associated both with the piston in the second cylinder and the holder and adapted to operate the latter when the piston works within the second cylinder, a two-way valve having passages for pressure and exhaust, and arms associated with said valve and capable of being acted upon for operating the valve and effecting admission and release of fluid pressure to and from the cylinders, whereby the pistons can be appropriately moved within the cylinders to operate the holder so that it grips a closure, move said holder to a container to be closed, effect rotation of the holder to apply the closure and subsequently return the parts of the unit to normal position, said units being disposed on the drum with their holders downwards, stationary tappets suitably spaced apart on the machine and adapted to act upon said arms at the required times, a container supporting shelf adapted to revolve with the drum and on which containers can be placed in alignment with the holders, means for rotating the drum and said supporting shelf so that the units can travel in company with the containers, means for bringing closures one at a time into a position to be received by the travelling holders, means for controlling the fluid pressure so that it can be cut off from the units for a prearranged period before release, means adapted to be acted upon by a container when it is initially presented to the machine for actuating the fluid pressure controlling means to admit pressure to the corresponding closure applying unit at the required time whereby such admission is obtained only in the event of a container being presented to the means for applying closure, and means which are normally in a position to operate the fluid controlling means to relieve the pressure in a closure applying unit near the point where a closure is initially presented to a container, said means being adapted to be rendered inoperative by a properly delivered closure, for the purpose herein described.

19. Apparatus for dealing with containers and closures therefor, comprising, in combination, a holder provided with members adapted to receive and grip a closure, means for operating said gripping members to grip said closure and means operable by fluid pressure for moving said holder towards and from a relatively stationary container to be dealt with and for imparting rotary movement to the holder, for the purposes herein described.

ARTHUR CLARKE.
